(57) **CLAIM**

The ornamental design for a rebar chair, as shown and described.

DESCRIPTION

FIG. 1 is a perspective view of a rebar chair according to one embodiment of the present disclosure;

FIG. 2 is an enlarged view of a lower leg and foot of the rebar chair of FIG. 1;

FIG. 3 is a bottom view of the foot of the rebar chair leg shown in FIG. 2;

FIG. 4 is a back side view of the rebar chair lower leg and foot shown in FIG. 2;

FIG. 5 is a right side view of the lower leg and foot shown in FIG. 2;

FIG. 6 is a left side view of the lower leg and foot shown in FIG. 2;

FIG. 7 is a perspective view of a rebar chair according to another embodiment of the present disclosure;

FIG. 8 is an enlarged view of a lower leg and foot of the rebar chair of FIG. 7;

FIG. 9 is a bottom view of the foot of the rebar chair leg shown in FIG. 8;

FIG. 10 is a back side view of the rebar chair lower leg and foot shown in FIG. 8;

FIG. 11 is a right side view of the lower leg and foot shown in FIG. 8; and,

FIG. 12 is a left side view of the lower leg and foot shown in FIG. 8.

The broken lines in the drawings illustrate portions of the rebar chair and form no part of the claimed design.
